UNITED STATES PATENT OFFICE.

HENRY F. KOHLHAGEN, OF SHEBOYGAN, WISCONSIN.

SET-SCREW COVERING.

No. 807,559.

Specification of Letters Patent.

Patented Dec. 19, 1905.

Application filed March 30, 1905. Serial No. 252,897.

To all whom it may concern:

Be it known that I, HENRY F. KOHLHAGEN, a citizen of the United States, and a resident of Sheboygan, in the county of Sheboygan and State of Wisconsin, have invented certain new and useful Improvements in Set-Screw Coverings; and I do hereby declare that the following is a full, clear, and exact description thereof.

10 My invention relates to devices for covering the set-screws on shafts and other moving parts of machinery, whereby the danger of accidents is largely eliminated; and it consists in certain peculiarities of construction and combination of parts, as will be fully set forth hereinafter in connection with the accompanying drawings and subsequently claimed.

In the said drawings, Figure 1 is a view, partly in elevation and partly in section on 20 the plane indicated by the line 1 1 of Fig. 2, illustrating a bit held by a set-screw to the spindle of a boring-machine, said set-screw being protected by my covering device. Fig. 2 is a plan view of said parts, partly in section on the plane indicated by the line 2 2 of Fig. 1. Fig. 3 is a view in elevation of my 25 said covering device. Fig. 4 is a sectional view of the same, taken on the plane indicated by the line 4 4 of Fig. 2.

30 Referring by numerals to the said drawings, 1 represents the boring shaft or spindle of a boring-machine, to which is secured a bit 2, whose shank 3 is held in place by a set-screw 4. The lower part 5 of said shaft or 35 spindle, which is formed with a bore for the reception of the bit-shank, is shown as of greater diameter than the upper part 1, so as to form a shoulder, as shown in Fig. 1. The part 5 and the set-screw 4 are surrounded by 40 an annular covering, here shown as made in two parts 6 6, like a split pulley, united by screws 7 7, introduced through holes 8 in one part and screwing into the edge of the other part, the two parts being centered by means 45 of laterally-arranged pins 9 9, set fast in the meeting edge of one part to project into corresponding semicircular grooves in the meeting edge of the other part, these pins being arranged in pairs, with the screws 7 between 50 their opposed inner ends, as best shown in Fig. 4, and thereby the heads of said screws 7 are entirely within the circumference of the covering 6 6. The said covering after the two parts have been fastened together is

slipped to place from one end of the shaft or 55 spindle, and the head of the set-screw 4 is received in an edge groove 10, which has inner side extensions 11 11, and then the covering is slightly turned, so that the head of the set-screw is within one or the other of said groove 60 extensions, the play of said covering being then limited in either direction longitudinally of the shaft or spindle. In this arrangement if it is desired to change a bit the covering is raised up and rested on the shoulder formed 65 by the increased diameter of the lower part 5 of the spindle 1, the set-screw 4 loosened, and another bit substituted, after which the shank of this new bit is secured by again tightening the set-screw and the covering turned to allow 70 the set-screw head to enter the groove 10 as the covering is dropped again to place and then turned, as before. It is immaterial whether a vertical or horizontal shaft is employed, as the covering will protect any projecting set-screw, and by always presenting a smooth outer surface all danger of the set-screw catching in the clothing of an operator or striking against him when the shaft is in motion is obviated. 80

These coverings may be made of any diameter desired, and if too large in any instance ordinary split bushings may be employed; but I have not deemed it necessary to illustrate such in the drawings, as their construction is well known. 85

Having thus described my invention, what I claim as new, and desire to secure by Letters Patent, is—

A set-screw covering consisting of a split 90 band, pins set fast in the meeting edges of one part of the band to project into corresponding grooves provided in the meeting edges of the other part of said band, and one of said parts provided with an inner edge groove having side extensions at one end, the latter groove being for the engagement of the head of a set-screw projecting from a shaft or spindle encircled by the covering, and screws uniting the aforesaid parts of the covering. 95

In testimony that I claim the foregoing I have hereunto set my hand, at Sheboygan, in the county of Sheboygan and State of Wisconsin, in the presence of two witnesses.

HENRY F. KOHLHAGEN.
